(57) **CLAIM**

The ornamental design for a camera lens hood, as shown and described.

DESCRIPTION

FIG. 1 is a front, top and right side perspective view of a first embodiment of a camera lens hood showing our new design; FIG. 2 is a front view thereof;

FIG. 3 is a rear view thereof;

FIG. 4 is a top plan view thereof, the bottom plan view being an identical image of FIG. 4;

FIG. 6 is a reduced left side view thereof;

FIG. 7 is an enlarged cross-sectional view taken along line 7-7 in FIG. 5;

FIG. 8 is a front, top and right side perspective view of a second embodiment of a camera lens hood showing our new design;

FIG. 9 is a front view thereof;

FIG. 10 is a rear view thereof;

FIG. 11 is a top plan view thereof, the bottom plan view being an identical image of FIG. 11;

FIG. 12 is a reduced right side view thereof;

FIG. 13 is a reduced left side view thereof; and,

FIG. 14 is an enlarged cross-sectional view taken along line 14-14 in FIG. 12.

The broken lines illustrate portions of the camera lens hood that form no part of the claimed design. The dash-dotted lines denote the boundaries of the claim and form no part of the claimed design.

1 Claim, 14 Drawing Sheets
